2 SHEETS—SHEET 2.

UNITED STATES PATENT OFFICE.

WILLIAM A. COCKE, OF CARTERSVILLE, VIRGINIA.

STUMP-PULLER.

1,265,612.

Specification of Letters Patent.

Patented May 7, 1918.

Application filed April 20, 1917. Serial No. 163,437.

To all whom it may concern:

Be it known that I, WILLIAM A. COCKE, a citizen of the United States, residing at Cartersville, in the county of Cumberland and State of Virginia, have invented certain new and useful Improvements in Stump-Pullers; and I do hereby declare the following to be a full, clear, and exact description of the invention, such as will enable others skilled in the art to which it appertains to make and use the same.

This invention relates to improvements in stump pullers.

The object of this invention is to provide a machine equipped with novel means for pulling stumps, roots or the like from the ground and also may be used as a lifting machine for raising heavy weights such as lumber, iron or the like and this machine is equipped with a mechanism whereby stumps may be pulled up or other materials lifted in a quick and reliable manner.

A still further object of this invention is to provide a stump pulling machine with a frame and having novel power applying mechanism arranged to be secured to the shaft for rotating the drums.

A still further object of this invention is to provide drums with novel means whereby the drums may be rotated in either direction.

A still further object of this invention is to provide a device of this character, which will be simple, practical and comparatively inexpensive in construction and one that can be manufactured and sold at a low cost.

With these and other objects in view, the invention consists in the novel combination and arrangement of parts hereinafter more fully described and set forth in the claims hereto appended.

In the drawings:

Figure 1 is a side elevation partly in section of my improved machine as made in accordance with this invention,

Fig. 2 is a top plan view of the same,

Fig. 3 is a transverse sectional view of the frame and drums,

Fig. 4 is a top plan view of the machine equipped with novel driving means,

Fig. 5 is a sectional view taken on the line 5—5 of Fig. 4,

Fig. 6 is a detail view illustrating the handle for moving the drums into and out of engagement with the gears carried by the shaft,

Fig. 7 is a fragmentary detail sectional view of the shaft and gear,

Fig. 8 is a fragmentary sectional view illustrating the manner in which the movable roller is swivelly connected by one end in the frame.

Like numerals of reference designate corresponding parts in all the figures of the drawings.

Referring to the drawings, the numeral 1 designates a rectangular frame in its entirety. The frame comprises a bottom rail 2, vertical end rails 3 and a top rail 4.

The top rail 4 is provided adjacent one end with a longitudinally extending slot 5 which communicates with and extends outwardly through the opening 6 arranged therein.

The opening 6 is adapted to receive the screw threads 7 of the shaft 8, a handle formed on the outer end of the shaft 8 to facilitate the moving of the shaft inwardly or outwardly in the slot 5 in the top rail of the frame. The inner end of the shaft 8 is enlarged as at 10 and has secured thereto a bearing collar 11 the purpose of which will be hereinafter more fully described.

A rectangular closure plate 12 is secured over the slot 5 in the top rail 4 by suitable fastening means 13 as illustrated in Fig. 4 of the drawings.

A relatively stationary drum 14 is journaled in the bottom and top rails of the frame adjacent one end thereof and this drum carries a gear 15 which is located inwardly beyond and in close proximity to the top rail 4 as illustrated.

A relatively movable drum 16 is journaled in the bottom rail as at 17 and has its opposite ends journaled in the bearing 11 on the inner end of the shaft 8 as illustrated thus facilitating the adjustment of the relatively movable drum with relation to the stationary drum.

A pair of gears 18 of different diameters are secured to the relatively movable drum adjacent the upper end thereof and in close proximity to the inner face of the top rail 4 as illustrated.

A shaft 19 is rotatably mounted in the top and bottom rails centrally thereof and has its upper end projecting upwardly beyond the outer surface of the top rail as at 20 which terminates in a reduced squared shank 21 which is adapted to receive an operating handle 22 thereon.

The portion of the shaft 19 located between the bottom and top rails is provided with screwthreads 23 which extend for a slight distance throughout the length of the 5 shaft 19 and adjustably receive the gear 24 which is limited in its threaded movement on the shank by the stop pins 25 arranged transversely through the shaft 19 and at a spaced distance apart.

10 The gear 24 when rotated in one direction is adapted to mesh with the gears 15 and 18 of the drums 14 and 16 and when moved upward on the shaft 19 and the drum 16 is moved inwardly it is adapted to mesh with 15 the gear 18' and gear 15 to cause rotation of the drum in different direction upon reverse rotation of the crank handle 22.

The lower end of the relatively movable drum is provided with a trunnion 25' which 20 terminates in a ball 26 which ball is adapted to rest in a bearing housing 27 removably secured to the exterior of the bottom rail 2. The inner surface of the bearing housing is provided with an inwardly tapering recess 25 28 which is adapted to receive the ball and the bottom rail is provided with an inwardly tapering opening which alines with the recess 28 to receive the ball 26 therein so as to permit pivotal movement of the relatively 30 movable drum therein so as to facilitate the moving of the movable drum with relation to the stationary drum.

The drum 14 carrying the gear 15 and the drum 16 carrying the gears 18 and 18' 35 are arranged to have engagement with one another through the medium of the gear 24 which is carried by the shaft 19. The gear 24 when rotated downwardly on the shaft 19 engages the gear wheel 18 of the drum 16 40 and the gear 15 of the drum 14 and it is to be understood that the gear 18 is of a larger diameter than the gear 15 carried by the drum 14 thereby upon rotation in one direction the drum 14 will make a greater speed 45 and have more revolutions than the drum 16. When the shaft is turned in the reverse direction the gear 24 moves upwardly, and the movable drum is moved inwardly thus meshing the gear 18' with the gear 24 and 50 the gear 15 whereby upon reverse rotation of the shaft the gear 18' being of a smaller diameter than the gear 15 the drum 16 makes more revolutions than the drum 14, the purpose of which will be hereinafter 55 more fully described.

A cable 29 has one end removably secured to the drum 14 as at 30 and its opposite end is wound about the drum 16 as at 31 and has a portion depending from the drum or 60 extending laterally from the drums as at 32 which is adapted to receive a pulley wheel 33 to which is journaled a U-shaped yoke 34 having connected to its web portion and eye 35 a flexible cable 36 which is adapted 65 to be wound about a stump or placed upon

material which is moved upon rotation of the drums through the medium of the shaft 19 and crank 22.

It can be understood that the drums can be used in either a horizontal or vertical position depending upon the manner in which the device is to be used for moving. When it is used as a stump puller, the drums can be set up in a vertical position and the cable 32 moved laterally therefrom and connected 75 to the stump which is designated A in the drawings.

When it is connected up with the stump in the manner described, the stump will be easily and quickly lifted, due to the fact that 80 there is comparatively no slack in the cable as a constant pull is obtained by one drum being rotated faster than the opposite drum.

Now referring to Figs. 4, 5 and 6, wherein there is shown a power operating mechanism 85 which facilitates the rotating of the drum, by any suitable power source, there is illustrated a frame 1, in which is a drum 14 and a movable roller drum 16. But instead of rotating the drums with the crank handle 90 22, there is secured to the upper end of the shaft 19, a gear 37, which is arranged on the squared portion of the shaft for rotation therewith.

The wheel 37 is a worm wheel or a worm 95 gear and is adapted to mesh with the worms 38 located on opposite sides thereof and swivelly connected as at 39 to the supporting plate 40 which is secured to the top rail 4 by suitable brackets 41. The opposite ends 100 of the worms 38 are pivotally secured as at 42 to the arms of the Y-shaped lever 43. A U-shaped frame 44 is secured by the ends of its legs to the opposite side edges of the top rail 4 as at 45 and its web is provided on its 105 upper side with a plurality of spaced notches 46 in which is adapted to be fitted the lug 47 carried by the stem of the Y-shaped lever 43. A spring 48 is secured as at 49 to the under side of the stem of the lever 43 and is adapted 110 to engage the web portion 44 of the U-shaped member to normally retain the lug 47 on the stem of the lever in one of the notches or recesses 46.

The supporting member 40 has journaled 115 centrally therein a shaft 50 which carries the gear wheel centrally of its ends designated 51, a pulley 52 is secured to the outer end of the shaft 50 which is adapted to receive a driving belt 53' which facilitates the 120 rotating of the shaft and gear 51, a pair of smaller gears 53 are rotatably mounted on the member 40 on opposite sides of the gear 51 and are adapted to mesh therewith and they have a shaft extending through and 125 pivotally connected to the inner and lower ends of the worms 38 as at 41.

When it is desired to use the power driven device with my improved stump puller the handle 54 is grabbed and the stem of the 130

Y-shaped member 43 is moved either to the right or left to turn a respective worm into engagement with the gear 37 whereby upon rotation of the shaft through the medium of 5 the pulley 52 the drums will be either rotated in the right or left direction.

What is claimed is:

1. A machine of the class described including a frame, a relatively stationary drum rotatably mounted in the frame, a relatively movable drum located in the frame and in close proximity to the stationary drum, a shaft rotatably mounted centrally of the frame, a gear carried by the stationary drum, a pair of gears carried by the movable drum, a movable gear carried by the shaft and adapted to mesh with the gears of the drums, said gear of the shaft adapted to move into engagement with 10 each of the gears of the movable drum for rotation in a reverse direction and means for moving the movable drum toward and away from the stationary drum, as and for the purpose specified.
2. A machine of the class described including a frame, a relatively stationary drum located in the frame, a gear carried by the drum, a relatively movable drum journaled in the frame, a pair of gears of 15 different diameter carried by the movable drum, a shaft rotatably mounted in the frame and located between said drums, a movable gear carried by the shaft adapted to mesh with the gears of each of the drums, 20 a means for moving the movable drum toward and away from the stationary drum, and a power applying mechanism secured to the shaft for rotating the drums in clockwise or counter-clockwise direction, said 25 gears being of different diameters to increase the rotation of one of the drums with relation to the other drum, a cable connected to one drum and wound about the other drum, as and for the purpose specified.
3. A machine of the class described including a frame, a stationary drum journaled in the frame, a gear carried by the drum, a movable drum journaled in the frame, a pair of gears of different diameters 30 carried by the movable drum, a shaft journaled in the frame and located between the drums, a movable gear carried by the shaft, said gear of the shaft adapted to mesh with the gears of the drums, means carried by the 35 frame and engaging the movable drum for adjusting the same toward and away from the stationary drum to increase or decrease rotation of the movable drum with relation to the stationary drum, and means for rotating the shaft and drums.

4. A machine of the class described including a frame, a relatively stationary drum journaled in the frame, a gear carried by the drum, a relatively movable drum swivelly connected by one end to the frame and its 45 opposite end being slidable in the frame, a pair of gears of different diameters carried by the movable drum, a shaft journaled in the frame and located centrally between the drums, a gear movable on the shaft adapted 50 to mesh with the gears of the drums, means extending through the frame journaled to the movable drum to facilitate the adjusting of the same toward and away from the relatively stationary drum to permit the increased rotation of one drum with relation 55 to the other, a cable connected to the relatively stationary drum and wound about the movable drum and means for rotating the shaft in either clockwise or counterclockwise 60 direction.

5. A machine of the class described including a rectangular frame, a relatively stationary drum journaled in the frame, a gear carried by one end of the drum, a relatively movable drum pivotally connected by one end to the frame, the opposite end being adjustably journaled in the frame, means extending through the frame at the movable 65 end of the drum for urging the same toward or away from the stationary drum, and gears of different diameters secured to one end of the movable drum, a shaft journaled in the frame and located centrally between the drums, a gear movable on the shaft, said 70 gear adapted to mesh with the gears of the movable and stationary drums, to facilitate the increased or decreased rotation of the drums with relation to one another, and a power applying mechanism secured to the 75 shaft for rotating the drums in clockwise or counterclockwise direction.

6. A machine of the character set forth comprising a frame, a drum, a gear carried by the drum, a second drum, gears of different diameters carried by the second drum, a shaft journaled in the frame and located between the drums, a gear movable on the shaft, and a drum shifting means located in the frame for engagement with the gears 80 of various diameters of the second named drum for moving them into mesh with the gear of the shaft for rotation with the shaft and other drum.

In testimony whereof I affix my signature 85 in presence of two witnesses.

WILLIAM A. COCKE.
